PEPPER MILL OR SIMILAR ARTICLE

Milan Mudrinich, 33—25 92nd St., Jackson
Heights, N.Y.

Filed May 16, 1963, Ser. No. 74,921

Term of patent 14 years

(Cl. D44—22)

The figure is a perspective view of a pepper mill showing my new design, the essential features of which reside in the bands of ornamentation which are continuous around the body of the pepper mill.

I claim:

The ornamental design for a pepper mill or similar article, as shown and described.
